HOT METAL CAR

John D. Pugh, Baltimore, Md.; Addie A. Pugh and F. Howard Smith executors of said John D. Pugh, deceased, assignors to said Addie A. Pugh, Baltimore, Md.

Application January 22, 1935, Serial No. 2,955

17 Claims. (Cl. 105—270)

This invention relates to mobile containers for molten materials, generally designated "hot metal cars" and to methods of operating the same in the transportation and distribution of such materials.

The present application is a continuation in part of my copending application Serial No. 722,555, filed April 26, 1934.

Mobile containers of this general type which are used for the transportation of molten material such as iron and steel from the point of origin in the steel plant to various points of destination, are well known in the art. These containers are mounted upon car structures for transportation along suitable trackways and are heavily insulated so that the material will remain in a molten state for long periods of time and be fluid when the car reaches its destination or discharge point. One form of hot metal car of this type which has proved highly useful in practice is disclosed in my Patent No. 1,251,282, issued December 25, 1917. The present invention contemplates the provision of a hot metal car which is somewhat similar in its broader aspects to that disclosed in the aforementioned patent, but which includes a number of novel features which, for certain purposes, make it more desirable than the car disclosed in my prior patent.

One object of the invention is the provision of a hot metal car which has a maximum capacity for a given weight, height and length. It is desirable, of course, to provide means for the transportation of large volumes of molten materials in a single batch, but without realizing excessive wheel loads upon the track and also without requiring a car of such length or height as to give rise to difficulties in rounding curves or clearing the usual overhead structures encountered on either standard railway or plant lines.

The hot metal cars of larger capacity give superior operating efficiencies over the smaller cars on account of the reduced unit radiating surface and the increased heat conservation; these thermal advantages permitting the delivery of hotter metal and a more fluid slag, resulting in the maintenance of cleaner ladles and extending the life of the lining thereof. In fact, the ladles of larger capacity have become practically self-cleaning.

However, the extra unit cost of the larger sizes of the older type hot metal cars tended to nullify the operating advantages referred to, whereas in the present case the lower unit cost of the

larger size of ladle rather enhances the operating advantages. These advantages are attained in the present case by the novel car structure in which the ladle is mounted directly on the trucks themselves without the interposition of car framing of any kind. In accordance with this invention, and for the purpose of permitting the container proper, which has the shape of a form of revolution with a horizontal axis, to have the largest possible diameter, the usual car under frame and end frames are dispensed with and the container itself is mounted directly upon wheel supporting trucks. This construction permits the maximum cross sectional area for any predetermined height limit of the container and supporting means. The novel hot metal car constructed in accordance with the present invention carries no dumping mechanism such as in previous cars of this type, the metal being withdrawn from the container by either of the two optional methods which will be later described, there being a great resulting saving in weight by reason of the omission of the heavy motor, gearing and framing usually employed in self-dumping cars.

The present invention contemplates the provision of a dual means for discharging the contents of the container, one of said means being described and claimed in my copending application to which reference has been made; that means permitting the discharge of the entire contents of the container without necessitating the tilting of the container body itself and without the provision of any special dumping mechanism associated therewith. This mechanism as pointed out in the prior application, comprises essentially a sealing cover for a port formed in the wall of the container at or near its top, a discharge tube preferably carried by the cover, and means for introducing compressed air or gas into the container above the level of the molten materials therein, the purpose being to effect the discharge of molten materials through the discharge tube under the complete control of the operator. The sealing cover, discharge tube and means for compressing gas are not carried by the car itself but positioned at the point of disposal or discharge so that such mechanisms add no weight or bulk to the car when it is in transit.

The second method of discharge may be applied to the unloading of either the entire contents of the container or of any portion thereof as, for example, the residue of slag remaining after the discharge of molten iron by the method

above described. This method also provides for the inversion and cleaning of the container when necessary. The connection of the container with its supporting trucks is so designed in accordance with the present invention as to prevent relative bodily movement in a horizontal plane but to permit the lifting of the container from the trucks for the purposes of this second dumping method. The novel disposition of these parts 10 permits the ready return of the container to its normal position after dumping.

In the various embodiments of the present invention illustrated and described in the present specification the hot metal car is moved to a 15 point on its trackway until it is positioned directly opposite certain fulcrums or skids supported closely adjacent the track. In some cases the skids or fulcrums are moved toward the container for engagement therewith, and in others 20 the exterior unloading means is mounted in a stationary position and adapted to be engaged by certain cooperating means on the container. When such contact is made between the container and the tilting means, the container is 25 lifted by means of a cable depending from an overhead crane, along a curved path about an axis passing between the points of contact of the supplemental unloading means and the cooperating portions of the container until it entirely 30 clears the trucks and may be thereafter rotated or rolled upon the unloading means until the port in the body of the container, which is normally positioned uppermost, becomes lowermost. Any molten material or other substance which may be in the container is, of course, discharged when such inversion takes place and furthermore it is then possible to examine the container interiorly to ascertain the condition of the lining or for other purposes.

40 Closely involved with these features is the peculiar and novel construction of the supporting trucks and this becomes an important object of the invention. In the illustrated embodiment there are provided truck bolsters of novel form 45 which are particularly adapted for supporting the container for tilting or rotation, and for transmitting the draft forces of the train.

Other objects and features of novelty will be apparent from the following description when 50 read in connection with the accompanying drawings in which certain forms of my invention are illustrated by way of example.

In the drawings:

Figure 1 is a plan view of a hot metal car 55 embodying the principles of my invention, with a portion thereof cut away to disclose certain features of the supporting trucks;

Figure 2 is a side elevation of the hot metal car, certain portions being cut away to better 60 illustrate the truck construction and container supporting means;

Figure 3 is an end view of the car and associated unloading mechanism;

Figure 4 is a transverse vertical sectional view 65 through a portion of the container and truck and showing the king pin and side bearing construction;

Figure 5 is a detail sectional view taken on line 5—5 of Figure 4;

70 Figure 6 is a similar detail sectional view taken through the corresponding side bearing at the other end of the container;

Figure 7 is a fragmentary sectional view similar to Figure 4 but illustrating a modification of the king pin bearing means;

Figure 8 is an end view of a hot metal car and unloading mechanism illustrating another embodiment of the invention;

Figure 9 is a similar view illustrating a further embodiment in which the container is rolled 5 along stationary unloading means;

Figure 10 is a view in side elevation of another form of hot metal car of less capacity than those illustrated in the earlier figures;

Figure 11 is an end view of the same car illustrating 10 one unloading method;

Figure 12 is a fragmentary view in side elevation of one end of the truck and bolster supporting this car;

Figure 13 is a transverse vertical sectional view 15 through the king pin and side bearings of the light weight car; and

Figure 14 is a plan view of one of the bolsters employed in this latter embodiment.

In the exemplary disclosures of the present invention, there are illustrated and described hot metal cars of two capacities: one of a rating of 200 tons, being illustrated in Figures 1-9 inclusive; and the other of a 75 ton capacity which is shown in the remaining figures of drawings. 25

The larger of these cars will be described first. In the pertinent figures of the drawings the container itself, designated generally by the reference numeral 10, has the shape of a form of revolution with a horizontal axis, and while it may 30 vary in its adaptations, it may be conveniently formed with a central cylindrical portion 11 and two outwardly tapering frusto-conical portions 12 which terminate in the end casting 15. The container is lined with suitable well-known insulating material indicated at 16 in Figure 4 and is provided with spouts 17 having ports 18 through which the metal is adapted to be poured or otherwise removed as will be hereinafter described in detail. 40

The ladle or container 10 is mounted directly upon the trucks 20 without the interposition of any car framing or platform. Each of the trucks 20 may be provided with ten wheels as shown and may comprise a properly equalized and balanced combination of a six wheel truck 21 and a four wheel truck 22. The six wheel truck is provided with an H-shaped bolster 23 having an intermediate portion 24 and four lateral projections 25 comprising spring seats for connection with the side frames of the six wheel truck. The four wheel truck 22 is provided with an ordinary transverse bolster 27. The bolster 27 is provided at its ends with side bearings indicated at 28 and the large bolster 23 is provided with the side 55 bearings 29. These bolsters are also provided respectively with center bearings 30 and 31. Supported upon these side and center bearings is the superbolster 35 which is shown partly in solid and partly in dotted lines in Figure 1, and very clearly 60 in side elevation in Figure 2 of the drawings. This superbolster is provided with pins which enter the center bearings 30 and 31 and with corresponding side bearing portions disposed above the side bearings 28 and 29 and having rollers or 65 other anti-friction means 36 interposed therebetween. The outwardly projecting end 38 of the superbolster 35 is designed to receive suitable draft mechanism with which is associated the coupler 39. 70

The inner adjacent ends of the trucks are flexibly and adjustably connected together as by means of the two curved springs 40 and the bolt 41. These connectors or spacers insure the maintaining of the proper spacing of the trucks during 75

the time that the ladle is removed for dumping purposes. The flexibility permits the free articulation of the trucks on curved tracks and the spacers are not intended to sustain any of the load applied to the draft gear since this is transmitted through the body of the ladle itself.

The frusto-conical portions 12 of the ladle are provided with saddles 45 centrally of which are formed the rounded king pins 46. It will be obvious to one skilled in the art to which this invention relates, that the saddles 45 which are of relatively small dimensions may be formed as an integral part of the wall of the container or they may be rigidly and permanently secured to the container wall in any suitable manner. Upon either side of the king pin each saddle is formed with the upper side bearing members 47. This construction is very clearly shown in Figure 4 of the drawings. Each of the superbolsters 35 is provided with the socketed center bearing members 48 and side bearing portions 49. Cylindrical rollers 50 are carried by the portions 49 and, at one end of the car, are normally spaced slightly from the upper side bearing parts 47. This spacing or clearance between the side bearing portions on the saddle 45 and the roller bearings 50 is omitted at the opposite end of the car. This feature is illustrated in Figures 5 and 6 of the drawings. This affords a substantially three-point suspension of the ladle on the two car trucks and permits a certain flexibility or tilting of the relatively elongated car when rounding banked turns. This arrangement, it will be understood, is only necessary in the case of exceptionally long cars of great carrying capacity. The three points of suspension referred to are, of course, the king pin at the end of the car at which the wider spacing of the side bearings occurs and the two side bearings at the opposite end of the car.

The method of discharging the molten contents of the car by means of pneumatic pressure is quite similar to that described in my copending application to which reference has already been made and will only be briefly referred to herein. The assembly which is adapted to be lowered in place upon the ladle, as by means of a crane stationed at the point of discharge, is indicated generally by the reference character 55. This assembly comprises the two cover plates 56 which are adapted to fit tightly over the ports 18 and are connected by the yoke 57. Renewable seats 56' are applied to the spout ports in order to render the covers air-tight and self-sealing. These seats are preferably made of a non-ferrous metal to which no molten metal will adhere and which may be readily cleaned. By means of suitable counterweighted, lost motion connections between the cover and the latch means indicated at 58, the cover arrangement is locked securely into place upon the spouts. The counterweight in this case is shown at 59. These features are described in detail in my copending application.

One of the covers 56 is provided with a discharge tube 60 which extends nearly to the bottom of the container and may be of any height, terminating at its upper end in the laterally directed spout 61. The crane hook for raising and lowering the pneumatic discharge mechanism is indicated at 62. In the operation of this discharge means, compressed air is introduced into the interior of the ladle preferably through the opposite cover 56 which, of course, is provided with an air hose or pipe coupling. Suitable check valves and air jets such as described in the application referred to are provided for controlling the

pressures and venting gases from the ladle. The discharge tube 60, 61 is provided at its upper end with an expansion chamber 65 which carries a hood 66 and is for the purpose of arresting any sparks or bubbles of molten iron which may be discharged at this point. With the covers clamped in position and the compressed air turned on, the molten metal will be forced out of the ladle and through the lower end of the discharge tube, thence upwardly through the tube 10 and out at the spout 61. Since the lower end of the tube extends to a point near the bottom of the interior of the ladle the pure metal will be discharged first and the slag which floats thereon will be discharged last; or, if desired, the slag may be retained for subsequent disposal at another point. Interruption of the discharge of molten material may be obtained by cutting off the air supply by a suitable controlling valve, and the pneumatic discharge device 55 may be removed by raising the crane hook 62 which will immediately unclamp the weighted latches or hooks 58 and permit the continued lifting of the hook 62, removing the entire device from the car.

The alternative method of unloading which involves rotatably removing the ladle from the car trucks will now be described. As depicted in Figures 1, 2 and 3 of the drawings there may be disposed alongside the track at the proper point a bifurcated runner 70 which is adapted to receive the molten material from the car and discharge it into the transfer ladles 72. Upon either side of the runner 70 are installed the spaced stands 75 which are located at the same distance apart as the ends 15 of the transporting ladle 10 of the hot metal car. These stands are provided with the fulcrum members 77 which project toward the track upon which the car is adapted to travel; and the stand is also provided at its upper portion with the toothed rack 78. One of the end castings 15 of the container is clearly shown in Figure 3 of the drawings. Upon the upper half or more of their peripheries they are provided with the toothed sectors 80, and projecting downwardly and outwardly from their lower portions are the legs 81 which are provided with concave seats 82. As the hot metal car approaches the delivery station the substantially cylindrical fulcrum projections 77 pass into the concavities 82 of the legs 81 and at this point the car is brought to a standstill. The members 77 are preferably provided with tapered and pointed projectile-like noses in order to be guided accurately into engagement with the leg portions 82. In order to rotate the ladle to dumping position the hooks 84, which are adapted to be raised by a suitable crane at the delivery station, are made to engage the lugs 85 which project from the cylindrical portion 11 of the ladle as shown clearly both in Figures 2 and 3 of the drawings. As the ladle is lifted by an elevation of the hooks 84, the container is rotated about the fulcrum 77 as a center and the toothed segments 80 are brought to mesh with the racks 78 on the stands 75. Further rotation of the ladle is then effected and it is caused to roll along the rack 78 until it reaches the position indicated in broken lines in Figure 3 whereupon the material may be discharged from the spouts 17 into the runner 70.

One of the most important features of construction of my improved hot metal car which enables this pouring method to be pursued will now be described. The king pins 46 which are received within the center bearings or sockets 48 of the car trucks are constructed, as clearly illus-

trated, with the lower portions thereof of less diameter than the upper, the king pins assuming an inverted dome shape which may be nearly hemispherical as shown in Figure 4 of the drawings or may be conical or of a similar downward tapering configuration. This arrangement permits the ready tilting or rotation of the car about an exterior fulcrum without interference of the king pin with its bearing or any other portion of the supporting trucks. As already indicated, the shape of each of the king pins may be hemispherical, conical or of any other downwardly converging configuration. The limitation of the profile of the king pins may be expressed as follows: All points on the surface of the pin remote from the fulcrum point shall lie within a circle drawn through the uppermost point of contact of said surface with the bearing socket about the fulcrum point as a center. The radius and arcs of this circle are indicated in certain of the figures of drawings at R. When the container is rocked about the axis represented by the fulcrums 11, the king pins, upon being lifted, will be freely drawn out of their recesses in the truck bolster and during the final lowering movement will freely enter the recesses; yet there is close engagement of the king pin surfaces with the correspondingly curved surfaces of the king pin receiving recesses at the center bearing of the bolster. The king pins are symmetrically formed in order that the container may be rocked in either direction from the trucks when being inverted.

An alternative form of center bearing for the superbolster 35 is suggested in Figure 7 of the drawings. A socket portion 87 is formed in the bolster and ball bearings 88 are retained therein by means of the annular ring 89 which also centers the king pin and receives horizontal loads from the draft gear and other sources.

In Figure 8, an unloading station is provided which employs extensible and retractible racks for engagement with toothed rings or segments on the car. A pair of these racks is provided as at 90 and each of these racks has toothed portions 91 which may be downwardly curved as at 92 at their forward ends. The unloading racks are adapted to mesh with the annular toothed rings 95 provided at the ends 15' of the ladies shown in Figure 8. The racks are supported for substantially horizontal movement upon the rollers 96 and 97, the horizontal flange 98 being provided at the rear end of each of the racks and being retained and guided by the small superposed roller 99. The forward ends of the racks are provided with undersurfaces which are inclined gradually as at 100 and more abruptly as at 101. The projection and retraction of the racks may be accomplished by any suitable driving means (not shown) which is made to actuate the screw 104 which transmits the force to the racks by means of the slide block 105 in the linkage 106. A portion of the stationary stand for supporting this operating mechanism is indicated at 107. The dotted line position of the rack shown in Figure 8 represents the retracted position thereof wherein the forward end is supported by the roller 97 contacting the inclined lower edge 100. As the racks are projected toward the hot metal car, which is brought to rest at the proper points along the tracks adjacent the unloading station, they are moved upwardly toward the toothed rings 95 of the container, gradually at first as the portion 100 moves along the roller and more abruptly as the portion 101 rides upon the roller 99 so that the teeth of the rack 91 are brought into

proper engagement with those of the ring 95. By means of the hook 109 which engages the proper connections 110 on the remote side of the container, the container may be rolled upon the racks until it is completely inverted as indicated in the dotted line position 111. This tilting and rolling movement is permitted by the similar downwardly tapering conformation of the king pin 112, the center of curvature of the profile of which is substantially at the points of initial meshing contact of the racks and toothed segments.

In Figure 9 there is shown an unloading arrangement in which the unloading racks are stationary and the portion of the track 115 adjacent the unloading station is movable laterally as by means of the supports 116. These racks are indicated at 117 and are shown mounted upon the stationary pedestals 118. The forward faces 119 of the racks are provided with teeth which face toward the container and are adapted to be engaged by the teeth 95' formed on the end discs 15' of the car when the track sections 115 are moved laterally toward the unloading station. The ladle is then rotated by means of the crane 25 hoists already described until it is brought to its inverted position as indicated in the description of the preceding embodiments.

As adapted to ladies or cars of smaller capacities, the invention is illustrated in the embodiment shown in Figures 10-14 of the drawings. This example is that of a 75 ton ladle which is also directly mounted upon the car trucks, thus affording the proportionate economies and reduction in weight as already described in connection with the 200 ton car. In this disclosure, the ladle indicated generally by the reference character 125 is of the same general configuration as the larger ladle, having an intermediate cylindrical portion 126 and end portions 127 of substantially frusto-conical shape. The end caps or castings 129 are provided with trunnions 130 for the attachment of crane hooks under certain circumstances and at their lowermost points are formed with the tapering king pins 132.

This smaller car is adapted to be mounted upon two four wheel trucks 135 disposed at the ends thereof. Substantially T-shaped bolsters 136, shown to best advantage in the plan view of Figure 14 of the drawings, are mounted upon the springs 137 by means of the spring seat portions 138. The transverse portions of the bolster members 136 are provided with center bearing members 140 which are designed to receive the tapered king pins 132 of the ladle and the side bearing tracks 142 which receive the barrel shaped roller side bearings 145. The end castings 129 of the ladle are provided with the laterally extending braced bearing portions 147 which rest upon the side bearing rollers 145 and are curved in substantial conformation to the peripheries of these rollers for a purpose to be hereinafter explained. The longitudinal portions 149 of the bolster members 136 are adapted to contain suitable draft gearing just as in the previously described embodiment and the couplers 150 are suitably connected thereto.

The two trucks 135 are adapted to be properly spaced apart, during the absence of the ladle from its transporting position, by means of the tie rod 152 which is adjustable in length as by means of the turnbuckle 153. The warping of the car due to unevenness of track levels as in rounding banked turns is sufficiently permitted in a car of this length by means of the bolster sup-

porting springs 137, and further means such as the described three-point suspension of the 200 ton car is not necessary in this instance.

The forward end 149 of the bolster 136 containing the draft gear may be given additional supporting means by the coiled springs 155 which lie beneath the flanges 156 and rest upon the cross bar 157 suitably secured to the ends of the trucks 135 as at 158.

10 Of course, pneumatic discharge apparatus may be employed in connection with this car similar to that described in case of the embodiment of larger capacity.

The dumping arrangement in this case, however, differs in some particulars from that of the larger car. The intermediate portion 126 of the ladle 125 is provided with the two ears 160 which are provided with the cylindrical bearing portions 161. Downwardly projecting ears or lugs 163 are also provided at the lower part of the intermediate portion 126 for the engagement of the hook of a dumping crane. Upon elevation of the crane hook applied to the projection 163 the ladle is rotated about the side bearing roller 145 upon the opposite side of the car to that upon which the engaged lug 163 is disposed. The side bearing members 147 on the ladle roll upon the curved surfaces of the roller 145 as the ladle rotates and the tapered king pin 132 moves out of its center bearing 140 clearing the walls thereof on account of the particular design of the king pin described herein. It will be noted that the walls of the king pin may be either curved or inclined just so that the lowermost portion of the side remote from the initial fulcrum point describes an arc which does not intersect any portion of the supporting bearing. The tilting of the ladle through a few degrees will bring the lugs or ears 160 into operative contact with the bearings 165 carried by the stands 166 mounted at the side of the track. This connection 160, 165 then becomes the fulcrum of the rotating ladle and further movement brings the ladle to the position 168 shown in dotted lines in Figure 11 of the drawings. It will thus be seen that during a short initial portion of the dumping movement of the ladle in this embodiment, the side bearings 145 form the fulcrum and during the latter portion of the dumping movement the fulcrum point is transferred to the bearing 165 on the stationary dumping stand.

Comparisons between the hot metal cars constructed in accordance with the present invention and others designed to perform similar functions make it very apparent that the present type of car is a most economical one to construct, operate and maintain. It has been found that, as compared with hot metal cars which carry power dumping means for instance, there is a most substantial saving in weight for all capacities and sizes of cars and that the actual saving in weight increases with increase in carrying capacity. Thus a typical car constructed in accordance with the present invention, having a capacity of 75 tons, may be designed to weigh as low as about 900 pounds for each ton of carrying capacity, and the same type of car designed to carry 200 tons of molten material may weigh only about 800 pounds for each ton of carrying capacity. The reverse is true with respect to cars of the motor dump type, for instance, one of these cars having a capacity of 75 tons weighing approximately 1260 pounds per ton of carrying capacity (as compared with 900 pounds) and a car having 200 tons capacity weighing about 1450

5 pounds for each ton of carrying capacity or, in other words, increasing in weight at a faster rate than increasing in capacity. The saving in first cost and cost of operation and maintenance is obvious.

It will be seen that, in its broader aspects, the present invention is applicable to all of the illustrated and merely exemplary embodiments as well as to many other variations which may be proposed, and, in any event, is only to be construed as limited in its scope by the following claims.

Having thus described the invention, what is claimed as new and desired to be secured by Letters Patent is:

1. A car for the transportation of hot metal or the like comprising a container and a mobile support therefor, the support including wheeled trucks having recesses, respectively, for the reception of king pins, a container normally resting on said trucks and having king pins rigid therewith, each of which projects within one of said recesses, the trucks being revoluble about the vertical axes of the king pins, and the king pins and recesses being so shaped as to permit ready removal of the container from the support by an upward rocking movement along a curved path about an axis located at one side of the container.

2. A hot metal car or the like comprising a pair of wheeled trucks, a container provided adjacent the ends thereof with king pins received within cooperating sockets in said respective trucks, side bearings between said container and said trucks which together with said king pins comprise the sole means of connection between said container and said trucks, said king pins being of some downwardly tapered configuration at least in a transverse plane whereby said container may be readily tilted or rotated about a fulcrum disposed laterally of said king pins for dumping purposes.

3. A hot metal car or the like comprising a pair of wheeled trucks, a container provided adjacent the ends thereof with king pins received within cooperating sockets in said respective trucks, side bearings between said container and said trucks which together with said king pins comprise the sole means of connection between said container and said trucks, spacing means between said trucks of insufficient strength to transmit the draft forces of a train, said forces being transmitted through said container and king pins.

4. A hot metal car or the like comprising a pair of wheeled trucks, a container provided adjacent the ends thereof with king pins received within cooperating sockets in said respective trucks, side bearings between said container and said trucks which together with said king pins comprise the sole means of connection between said container and said trucks.

5. A hot metal car or the like comprising, in combination, a plurality of wheeled trucks each provided with a bolster and a center bearing, a container provided with a king pin adapted to be received by said center bearing, and draft gear carried by said bolsters and disposed in substantially the same horizontal line as said king pin and center bearing connection.

6. A hot metal car or the like comprising, in combination, a pair of multiple wheeled trucks each comprising a pair of smaller trucks having bolsters resiliently mounted thereon, a superbolster supported by the bolsters through the intermediary of center and side bearings, a con-

tainer provided with a king pin adjacent each end thereof and adapted to be pivotally supported by bearings in the respective superbolsters.

7. A hot metal car or the like comprising, in combination, a pair of multiple wheeled trucks each comprising a pair of smaller trucks having bolsters resiliently mounted thereon, a superbolster supported by the bolsters through the intermediary of center and side bearings, a container provided with a king pin adjacent each end thereof and adapted to be pivotally supported by bearings in the respective superbolsters, and draft gear carried by said superbolsters.

8. A hot metal car or the like comprising, in combination, a wheeled car truck, center and side bearings thereon, a tilttable container carried thereby and provided with a hemispherical king pin seated in a similarly shaped socket in the center bearing.

9. A hot metal car or the like comprising, in combination, a wheeled car truck, center and side bearings thereon, a tilttable container carried thereby and provided with a hemispherical king pin seated in a similarly shaped socket in the center bearing, and a plurality of anti-friction members contained within said socket for rotatably supporting said king pin.

10. A unit of railway rolling stock of the class described comprising a pair of wheeled trucks each provided with side and center bearing members, an elongated load container supported at each of its ends by one of said trucks, center bearing members on said container resting on the center bearing members of said respective trucks and side bearing members cooperating with the side bearing members on said trucks, the side bearing member on said container and one of said trucks being provided with a substantial clearance therebetween, but no clearance being provided between the side bearing member of the container and the other truck, whereby the necessary flexibility is provided to permit weaving of said unit upon an uneven track.

11. The combination of a hot metal car or the like with means for discharging the contents thereof comprising a container mounted upon wheeled supporting trucks, cooperating side and center bearing elements on said trucks and said container, said side bearings including convex anti-friction rollers permitting rotation of said container about said rollers as a fulcrum for unloading purposes.

12. The combination of a hot metal car or the like with means for discharging the contents thereof comprising a container mounted upon wheeled supporting trucks, cooperating side and center bearing elements on said trucks and said container, said side bearings including convex anti-friction rollers permitting rotation of said container about said rollers as a fulcrum for unloading purposes, said center bearings comprising king pins and cooperating sockets therefor, the transverse curvature thereof being substantially centered about said rollers whereby

upon rocking movement of the container about said rollers said center bearing elements may be readily parted.

13. A car for transporting hot metal and the like comprising a container member and a mobile supporting member, the container member normally resting upon the supporting member, one of said members having a plurality of projecting elements which normally project within corresponding recesses in the other, the interengaging elements and recesses being disposed beneath the container and preventing relative bodily rectilinear movement of the said members in any direction in a horizontal plane but permitting the container member to be lifted from the supporting member along a curved path about an axis positioned to one side of the container, whereby when the container is in its normal position for travel and the projecting elements and recesses are engaged, draft stresses may be transmitted through the elements between the container and the mobile supporting member.

14. A car for transporting hot metal or the like comprising a plurality of wheeled car trucks, a container having means rigid therewith adapted to directly engage and bear upon said trucks, whereby the trucks directly support the container, and means for preventing relative rectilinear movement of said container and trucks in a horizontal plane, whereby draft forces may be transmitted between said trucks through said container, said container being freely removable from said trucks by the application of lifting forces thereto.

15. A car for transporting hot metal or the like comprising two spaced car trucks, a container having means rigidly secured thereto which is adapted to engage cooperating means rigid with the car trucks, respectively, whereby the trucks directly support the container, said cooperating means rigid with container and trucks respectively permitting the container to be freely removed from the trucks by the application of lifting forces to the container, while permitting the trucks to swivel relatively to the container and preventing relative rectilinear movement of the container and trucks upon the application of draft forces.

16. A car for transporting hot metal or the like including a wheeled car truck, a hot metal container, and means for connecting said container to and mounting it directly upon said truck, said means comprising interengaging members rigid with the container and truck respectively which permit the truck to swivel with respect to the container while preventing relative rectilinear movement thereof.

17. A hot metal car or the like comprising, in combination, two wheeled trucks each provided with a bolster and a center bearing, and a container having king pins rigidly secured to its undersurface adjacent the container ends, said king pins being adapted to be received by said center bearings, and draft gear carried by said bolsters.
